UNITED STATES PATENT OFFICE.

EDWARD MITCHELL, OF ST. CHARLES, ILLINOIS, ASSIGNOR TO FRIEDELEY-VOSHARDT CO., OF CHICAGO, ILLINOIS, A CORPORATION OF ILLINOIS.

DESIGN FOR A SHOWER-PAN FOR LIGHTING-FIXTURES.

47,266.

Specification for Design.

Patented Apr. 27, 1915.

Application filed March 6, 1915. Serial No. 12,633. Term of patent 3½ years.

To all whom it may concern:

Be it known that I, EDWARD MITCHELL, a citizen of the United States, residing at St. Charles, in the county of Kane and State of Illinois, have invented a new, original, and ornamental Design for Shower-Pans for Lighting-Fixtures, of which the following is a specification, reference being had to the accompanying drawing, forming part thereof.

Figure 1 is a side elevation of a shower pan for lighting fixtures, showing my new design. Fig. 2 is a plan view of the same.

I claim:

The ornamental design for a shower pan for lighting fixtures, as shown.

EDWARD MITCHELL.
